ATHLETIC SHOE

Howard M. Pierce, John H. Hermson and Nils H. Thorkelson, Brooklyn, N. Y., assignors to A. G. Spalding & Bros. Inc., New York, N. Y., a corporation of Delaware

Application July 1, 1938, Serial No. 216,937

3 Claims. (Cl. 12—142)

The present invention relates to improvements in turned shoes and to a new method of making the same.

It is the principal object of the present invention to provide a turned shoe which possesses greater flexibility of its shank portion than shoes made according to previous proposals.

Another important object of the invention is to provide a shoe with a shank portion of greater flexibility, having increased strength and resistance to wear.

The principal feature of the invention resulting from the attainment of these objects is a new method of producing a turned shoe which broadly resides in securing the shank portion of the upper to the sole in a manner different from the securing of the forward portion.

Another important feature of the invention for attaining the above objects consists in reducing the thickness of the shank portion of the sole as such and building up sections of the reduced portion with a layer or layers of tougher and more flexible material.

A further feature of the present invention is the provision of a flexible sole extending the entire length of the shoe, and an upper which is stitched to the outer edge of the sole only at the forward portion thereof and is provided with shank extensions overlapping the shank portion of the sole and secured thereto intermediate the outer edges of the sole.

Further objects of the present invention are the provision of a new method of making turned shoes which requires less hand work, and less time and manufacturing cost than similar methods heretofore proposed.

For attaining the latter objectives, the present invention provides a new method of obtaining an improved product by reducing the amount of hand work and omitting certain manufacturing steps which were necessary according to previous proposals for obtaining a similar product and substituting for certain complicated and expensive steps of such prior proposals others which are simpler and less expensive, yet producing superior product.

These and other objects, features and advantages of the present invention will be apparent from the following detailed description and the accompanying drawings in which:

Figure 1 is a plan view of the sole according to the invention, prior to stitching.

Fig. 2 is a side view of Fig. 1.

Fig. 3 is a bottom view of the shoe prior to

turning and showing different stages of manufacture.

Fig. 4 is a top view of the completed shoe.

Fig. 5 is a bottom view of the completed shoe.

Fig. 6 is a cross-section along line 6—6 of Fig. 5.

Fig. 7 is a cross-section along line 7—7 of Fig. 5.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Referring now to the drawing in detail, the present invention provides a flexible main sole 10 which extends through out the length of the shoe 11 and consists of a forward portion 12, a heel portion 13 and a shank portion 14 intermediate the forward and heel portions. The forward portion 12 is provided at one side 15 with a groove 16 adjacent its outer edge and a split portion 17 forming a channel 18 and a closing lip 19. As clearly shown in Fig. 1, the groove 16 and split portion 17 only extend from the front end of the sole to the front end of the shank 30 portion 14. The heel portion 13 is cut away or notched at its front end at 20 to produce shoulder 21, and is provided at the other side 22 with a groove 23, and a channel 24 similar to those of the forward portion 12.

As already indicated, grooves 16 and 23 and channels 18 and 24 of the forward and heel portions, respectively, only extend to the front and rear ends of the intermediate shank portion 14 so that the latter is free of any channel or groove. However, according to the present invention and as shown in Figs. 2 and 7, shank portion 14 is reduced in thickness relative to the front and heel portions 12 and 13 immediately adjacent the rear end of the split or channeled portion 17 and at the same side 15, which in the final product constitutes the upper or inner side of the sole. This reduced shank portion 14 is furthermore graded down or recessed toward the outer edges, as shown particularly in Fig. 7.

The upper 25 and the lining 26 which are cemented and stitched together and provided with reinforcements at the toe and heel parts, are then molded in inverted position over a last on which the sole 10 is applied with side 22 facing the

last. Then they are fitted over the outer edges of the sole and tacked to the other side 15 of the sole. Thereafter, the upper and lining are sewed along the edge 21 to the forward portion 12 of the sole only by stitches 28 passing transversally through the upper and lining 25 and 26 and the channel 18, as shown particularly in Fig. 6.

After thus stitching together the forward portions of the sole 10, the upper 25 and lining 26 from the front end of the shoe along both sides approximately to the forward end of the shank portion 14, the end portions of the upper and lining projecting above the seam stitches 28 are trimmed or cut away at both sides of the sole 10 from the forward end approximately to a line 29 intersecting the ball portions of the sole, as shown particularly in Fig. 3. The remainder of such projecting portions of the upper and lining at both sides of the shoe extending from line 29 to the forward end of the heel portion 13, thus constitute a pair of double-layer shank extensions 30 and the layers of each pair are of substantially equal length and width as shown in Figs. 3 and 7 of the drawings.

After completing the trimming operation, the shoe is removed from the last, and the double-layer shank extensions 30 machine-stitched to the reduced or recessed shank portion 14 of the sole by a line of stitches 31 parallel but spaced from each outer edge of the sole 10 adjacent the inner end of each extension 30 and extending substantially from line 29 to the forward end of the heel portion 13, as shown particularly in Fig. 4. Thus, stitches 31 pass through both layers of each shank extension 30 and secure the same to the main sole 10.

Thereupon, the shoe is turned inside out, and each double-layer shank extension 30 is again machine-stitched to the sole by an outer line 40 of stitches 32 substantially parallel with the inner line of stitches 31 and closely adjacent the respective outer edge of the sole 10, but only extending substantially to the rear end of the split or channeled portion 17 and transverse 45 stitches 28.

A tap sole 33 is then applied to the forward portion 12 of the main sole 10 and sewed thereto by a row of stitches 34, shown in Fig. 6, passing 50 through the grooved portion 16 adjacent the outer edges of the sole 10. Thence, a welt 35, shown in dotted lines in Fig. 5, is sewed to the heel portion 13 by transverse stitches passing 55 through the channel 24 to fill out the groove 23, and a heel lift 36 which extends from the rear end of the shoe to a line adjacent but in front of the rear end of the shank portion 14 so that it overlies the rear ends of the shank 60 extensions 30, is sewed along its outer edge to the welt 35 and the rear end 37 of the shank portion 14 of the sole 10.

Finally, for securing the shank ends of the tap sole 33 and the heel lift 36 to the main sole 10, transverse rows of machine stitches 38 are provided adjacent the rear edge of tap sole 33, and 65 a similar row of stitches 39 adjacent the breast of the heel lift 36. As shown in Figs. 4 and 5, these stitches 38 and 39 also pass transversally through shank extensions 30 near their respective outer ends and thus act as a further securement and reinforcement of the shank extensions.

By the new structure and method according to the present invention, a shoe is obtained which has heretofore unsurpassed flexibility of its shank portion and therefore is especially adapt-

ed for use in various sports. Such flexibility is obtained by reducing or recessing the shank portion of the main sole 10 and filling out a part of such reduction by the double extensions 30 of the upper and lining. Since the leather of such upper and lining is of considerably finer grain, greater flexibility and toughness than the leather of the main sole 10, the shank portion of a sole which is built-up according to the invention of a thin layer of sole leather and a double layer 10 of upper leather possesses not only increased flexibility over the usual coarse-grained main sole of uniform thickness, but also increased strength and resistance to wear. Actual tests have shown that the flexibility of the shank portion of the new shoe is considerably improved over similar type shoes made according to various proposals prior to the invention. It has also been found that such increased flexibility and strength is due to a large part to the particular method of 20 stitching and the particular position of the rows of stitches which secure the shank extensions 30 to the main sole 10.

For example, according to some previous proposals, the upper and lining were sewed by a 25 transverse row of stitches to the edges of the main sole not only at the forward portion thereof but also at the shank portion, and a welt or reinforcing strip had to be added to protect the transverse stitches and prevent the upper and 30 lining from tearing loose from the shank portion of the sole. Such reinforcing strip obviously reduced the flexibility of the shank portion considerably.

If, on the other hand, the shoe is made according to the method of the present invention by extending the shank portions of both upper and lining inwardly of the shoe and securing each of them to the main sole 10 by double rows of 40 stitches spaced inwardly from the outer edges of the sole and passing vertically through the sole, the strain on the stitching by the flexing of the shoe during use is reduced. Thus, the upper and lining cannot be torn from the sole and a reinforcing strip or welt becomes superfluous.

Furthermore, since the vertical stitching of the shank portion of the shoe is performed within the full vision of the workman, the shank extension can be pulled in more tightly than if 50 transverse or hidden stitches were used at this portion and placed in channels such as 18. The shank portion of the shoe therefore fits tightly around the shank of the foot, giving the same improved support without the addition of special 55 strengthening means.

Another important advantage of the present invention is a considerable reduction in the cost of manufacture of the new shoe as compared with the cost of making the shoe according to previous 60 proposals. All of the stitching of the shank portion is carried out by a simple sewing machine, while the shank portions of all similar shoes as heretofore proposed required either manual stitching or complicated machinery. Thus, the 65 cost of skilled labor is materially reduced and the high initial expense for special machinery is avoided, while at the same time a superior product is obtained.

Variations and modifications may be made 70 within the scope of this invention and portions of the improvements may be used without others.

Having thus described the invention, what is claimed as new is:

1. A shoe comprising a main sole having a 75

forward portion including a ball portion, a heel portion, and a shank portion of less thickness than said forward and heel portions; said reduced shank portion having reduced margins; said forward portion having a groove adjacent its outer edge and a channel spaced from said groove; an upper and a lining, each having forward, shank and heel portions; stitching within said channel securing the forward portion of the upper and lining to the wall of said groove; a pair of spaced shank extensions of substantially equal width and integral with said upper and lining, at the sides of the shoe and overlapping the reduced margin of the shank portion of the main sole; and spaced longitudinally extending lines of stitching passing vertically through the double-layer shank extension and main sole, at both sides of the shoe.

2. A shoe comprising a main sole having a forward portion including a ball portion, a heel portion, and a shank portion of less thickness than said forward and heel portions; said reduced shank portion having reduced margins; said forward portion having a groove adjacent its outer edge and a channel spaced from said groove; an upper and a lining, each having forward, shank and heel portions; stitching within said channel securing the forward portion of the upper and lining to the wall of said groove; a pair of spaced shank extensions of substantially equal width and integral with said upper and lining, at the sides of the shoe and overlapping the reduced margin of the shank portion of the main sole; spaced longitudinally extending lines of stitching 35 passing vertically through the double-layer shank extension and main sole, at both sides of the shoe; a tap sole and a heel lift secured to the forward and heel portions, respectively, of said main sole; and transverse lines of stitching adjacent the shank ends of the tap sole and heel lift, and

passing through the double-layer shank extensions, the main sole and, respectively, the tap sole and heel lift, said longitudinal stitching extending substantially from the transverse line of stitches passing through the heel lift to the ball portion and beyond the transverse line of stitching passing through the tap sole.

3. A method of making a flexible turned shoe comprising the steps of providing a highly flexible sole of uniform thickness at one side with a groove extending around the forward portion substantially to a line intersecting the ball portions of the sole and a channel adjacent the groove; and a shank portion having a reduced portion extending thereacross at the grooved side thereof and a further reduced margin at each side; stitching through the channel and an upper and lining for securing the upper and lining to the wall of the groove; trimming the projecting end portions of the upper and lining around the forward portion of the sole substantially to said intersecting line so as to leave spaced pairs of superimposed shank extensions of said upper and lining of substantially equal width at either side of the shoe; stitching through said sole and shank extensions at each side of the shoe along a line substantially parallel with but spaced inwardly from the respective outer edge of the sole and extending from the rear end of said shank extensions to said intersecting line so that the shank extensions fill out substantially the reduced margins of the shank portion of the sole; turning the shoe; and stitching through said sole and shank extensions at each side of the shoe along a line substantially parallel with but spaced from the last-mentioned line.
